UNITED STATES PATENT OFFICE

FRANK J. KRISTOFEK, OF ST. PAUL, MINNESOTA, ASSIGNOR TO BROWN & BIGELOW, OF ST. PAUL, MINNESOTA, A CORPORATION OF MINNESOTA

PENCIL

Application filed May 7, 1924. Serial No. 711,683.

My invention relates to an improvement in pencils, wherein the primary object is to provide means to cover the working parts of the pencil within the barrel and cap or operating head with a suitable material of the same nature to provide a uniform outer appearance to the pencil in an inexpensive manner and by using the smallest number of parts possible in the completion of the same.

10 It is also a feature of my invention to provide an eraser cap for the pencil which is adapted to frictionally engage over the eraser socket to conceal the eraser and socket within the cap and to provide an annular bead projecting from the open end of the cap which forms an ornamental design in relation to the pencil barrel when the cap is in operating position on the same.

15 A further object of my invention resides in a pencil wherein a unit lead propelling means is held within the pencil barrel in a manner so that the threaded member of the propelling means forms a lead magazine in relation with the pencil barrel when the same is held circumferentially positioned within the barrel. The threaded member is provided with a knurled portion which is positioned adjacent and projects from the rear end of the pencil barrel. This knurled portion is 20 covered by means formed on the eraser cap of the pencil.

25 The invention also includes an eraser cap which is provided with ornamental means formed therein adapted to engage against a shoulder formed on the propelling member to limit the position of engagement thereon, to cover the same shoulder and the knurled portion together with the rear edge of the pencil barrel to conceal the same under the cap.

30 The invention includes other features and means which will be more fully set forth within the following specification and claims.

45 In the drawings forming a part of this specification:

Figure 1 is an enlarged side sectional view of my pencil, a portion of which is broken away,

50 Figure 2 is a side view of the threaded and

magazine member of the propelling means removed from the pencil barrel,

Figure 3 is a side view of the operating member of the propelling means removed from the threaded member and pencil barrel, 55

Figure 4 is an enlarged cross sectional view of the head or cap for the eraser and operating end of the pencil.

In the drawings A represents my pencil which is provided with the barrel 10 formed 60 of metal or other suitable material and at the rear end of which is positioned the operating head with its cap 11 which is turned in a manner to operate the propelling means of my pencil.

65 The propelling means of my pencil is of a unit construction and is made up of the members 12 and 13 which are held together by means of the spring sleeve lock 14 freely journaled on the operating head 15 of the 70 member 13 which also constitutes a supporting means for the eraser 16 which is held in a socket formed in the end of the head 15. The locking sleeve 14 frictionally engages within the sleeve end 17 formed and positioned on the member 12 to hold the member 13 against free longitudinal movement in the member 12 and in operating position.

75 The member 12 is centrally positioned within the pencil barrel 10 in a manner to 80 provide an annular lead magazine 18 about the member 12 and between it and the barrel 10 so that extra marking leads 19 are loosely held positioned in the magazine 18.

85 The member 12 is held within the pencil barrel 10 by the threaded portion 20 formed on the sleeve portion 17 which engages in the complementary thread, (not shown), formed within the rear end of the pencil barrel 10, to hold the magazine member 12 90 with its threads fixed against movement when in operating position within the pencil barrel.

95 A knurled portion 21 is formed on the outer end of the sleeve portion 17 which provides suitable means for engaging the member 12 so as to remove it from the pencil barrel 10 or to securely lock it within the same. The knurled portion 21 is positioned adjacent to the rear end 22 of the pencil 100

barrel 10 and projects from the same so that it can be easily engaged.

The cap 11 is formed with a cylindrical portion 23 which frictionally engages over the operating head 15 so as to fix the cap firmly thereto and permit the member 13 to be rotated to operate it with its lead pusher and carrier 24 back and forth within the member 13 to propel and repel the marking lead 19.

- 10 The cap 11 is removable from the member 15 to expose the eraser 16 but engages the member 15 with sufficient friction to hold the cap against disengagement from the member 13 when it is desired to selectively withdraw the member 13 from the member 12 and pencil barrel without removing the member 12 and to permit the full or partial withdrawal of the member 13 from the pencil A to expose the knurled portion 21 so that it 20 can be engaged to permit the removal of the portion 12.

The cap 11 is formed with a projecting ornamental bead 25 which is of sufficient size to cover and conceal the knurled portion 21 and to project over the rear edge 22 of the pencil barrel 10. In this manner the cap 11 forms a concealing means for the projecting ends of the propelling unit B which is made up of the member 12 and 13 so that the cap 30 11 conceals the same when the parts are in operating position in the pencil.

The portion 15 is formed with an annular projecting shoulder 26 which limits the inward position or engagement of the cylindrical portion 23 of the cap 11 on the portion 15. This prevents the cap 11 from being forced 35 too far onto the rear end of the member 13 and forms a stop against which the inner edge of the bead 25 engages to hold the cap in position.

It is very desirable to provide pencils of this nature with the barrel 10 and the cap 11 of precious metal such as gold, silver and the like, and in such case it is absolutely essential 45 that the general outward appearance of the pencil be entirely uniform to give a finished attractive appearance. This is fully accomplished by means of my cap 11 with its ornamental design to form an engaging head 50 together with the formation of an ornamental bead of a design adapted to permit means for covering the knurled portion 21 and the projecting portions of the propelling unit.

65 The peculiar construction of my propelling unit having separable members positioned one within the other which is removable as a unit from the pencil barrel or the operating member is selectively and independently removable from the unit and pencil together with the knurled engaging portion 21 positioned projecting from the projecting barrel in a manner so as to be readily engaged when 65 exposed provides a novel construction of a

very simple nature which is a valuable feature of my invention.

In accordance with the patent statutes I have described the principles of operation of my invention together with the construction which I now consider to represent the best embodiment thereof and while I have illustrated a particular form in the drawings I desire to have it understood that this is only illustrative and that the invention can be carried out by other means applied to uses other than those above set forth within the scope of the following claims.

I claim:

1. In a pencil wherein the propelling means is separable in relation to itself and removable from the pencil barrel and the two parts of which are exposed at the rear end of the barrel, a shoulder on the rearmost of the two said parts, a cap adapted to engage a portion of said rearmost part against said shoulder and conceal the exposed portion of the other of said parts.

2. A pencil including a barrel, a lead propelling unit removably held within said barrel, said unit being composed of several members held together in operative relation, a knurled engaging portion formed on one of the members of said unit, a shoulder formed on the other member of said unit, and a cap adapted to slide over said last mentioned member into engagement with said shoulder, and having a portion projecting beyond said shoulder adapted to form a concealing bead adapted to cover said knurled portion when the cap is in operative position.

3. A combination with a pencil including a barrel open at the upper end, a sleeve inserted in said open end of the barrel having a knurled portion abutting the upper end of the barrel, and a propelling member inserted in said sleeve and having a head projecting out of the sleeve of a cap having a body portion adapted to frictionally fit on said head, and having an enlarged portion extending freely beyond the head to conceal the joints between the barrel, sleeve and head, and stop means on the cap and head to limit the inward movement of the cap.

4. A cap for a pencil in combination with a pencil part which includes a barrel open at the upper end, a sleeve inserted in said open end having a knurled portion abutting the upper end of said barrel, a propelling member insertable in said sleeve and having a head projecting out of the same, said cap including a body portion adapted to frictionally engage said head and an enlarged portion extending freely beyond said head to conceal the joints between the barrel, sleeve and head.

5. A pencil including a lead-propelling unit having members positioned one within the other and each having portions at the rear exposed for gripping and the exposed portion

of the inner of the members having an external shoulder substantially spaced from its rear end, and a cap fitted on said rear end having an interior shoulder to engage said exterior shoulder and limit forward movement and having extension beyond said internal shoulder to cover the gripping portion of the other of said members.

5 6. A cap for the operating head of the lead-propelling means of a pencil, said cap having a wide covering bead formed annularly in the free edge of said cap and providing a stop shoulder, the operating head having a shoulder to engage therewith to limit the movement of said cap onto the head and which said bead is adapted to cover.

10 7. A pencil operating cap including a wide covering bead formed annularly in the free opened edge of said cap in combination with 20 a barrel and lead operating member for a pencil, the pencil including an annular shoulder formed on said lead operating member adapted to form a stop shoulder for said cap and over which said wide covering bead 25 is adapted to project, said wide covering bead having a nature to extend beyond said shoulder on said lead operating member and over the rear edge of the pencil barrel.

15 8. A cap for a pencil of the type in which 30 a propelling means projects out of the rear end of a barrel and an operating member projects out of the rear end of the propelling means, including a front portion adapted to engage snugly upon the end of the operating 35 member, an annular projecting bead formed on the inner edge of said cap having an enlarged nature, said bead having its outer edge enlarged to clear and extend over a portion of the pencil barrel and the propelling means carried by the pencil barrel.
